UNITED STATES PATENT OFFICE.

WILLIAM JOHNSTON FRAME, OF GLASGOW, SCOTLAND.

HYDRAULIC-JET SUCTION APPARATUS.

1,068,755.

Specification of Letters Patent. Patented July 29, 1913.

Application filed February 18, 1911. Serial No. 609,526.

To all whom it may concern:

Be it known that I, WILLIAM JOHNSTON FRAME, a subject of the King of Great Britain, residing at Glasgow, Scotland, have invented certain new and useful Improvements in Hydraulic-Jet Suction Apparatus, of which the following is a specification.

This invention relates to hydraulic suction apparatus of the type wherein one or 10 more jets of water are employed the water being sprayed or atomized and directed into an eduction tube.

In the specification of my prior U. S. Patent No. 924,335, issued 8th June, 1909, 15 I have described an apparatus of the above type wherein liquid jets pass through a diaphragm and are caused to impinge so as to be finely broken up or atomized and also diffused or spread to such an extent as, in 20 this finely divided state, to more or less completely fill the bore of an eduction or diffusing tube and, while becoming thoroughly mixed with the air or gas therein, to entrain or set the same in motion and carry the 25 same forward through the eduction tube thereby creating a very powerful suction, the eduction tube being provided with a number of conic contractions which deflect and concentrate or combine the traveling 30 mass of air and water. This apparatus has given very good results.

I have made a number of experiments in connection with the flow of water through different kinds of orifices and I have found, 35 if the entrance edge of an orifice (the wall of which must not converge) is sharp and the surface surrounding the orifice is more or less flat, that the water entering the orifice from all sides cascades over the edge 40 thereof and its molecules impinge upon one another a short distance below the orifice and are atomized and spread owing to the re-action produced by the impingement. Owing to the cascading action a full flow 45 of water does not take place through the orifice but a partial flow and this partial flow takes place so long as the length of the parallel part (or wall) of the orifice is not so great, compared with the least dimension 50 of the entrance opening, as to cause a vacuum to take place next the wall of the orifice; as, if a vacuum does take place then a full flow immediately results owing to the rush of water to fill the void. If the orifice has 55 a wall which is partly parallel then ordinarily the parallel wall or part of the ori-

fice should not be greater in length than about the least transverse dimension of the opening.

Under this invention I economize the 60 water and, at the same time, obtain even greater efficiency than with an apparatus as constructed in accordance with my said former patent, by making the hydraulic suction apparatus operate with a (or more 65 than one) jet of water which passes through an orifice so shaped that the cascading action aforesaid takes place the water being very thoroughly atomized and traveling forward with but very slight diminution of the original 70 velocity of discharge. In order to obtain the maximum efficiency it is necessary that the sprayed jet should be directed across the suction space or chamber of the apparatus into an eduction tube having a series 75 of truncated cones therein, as in my prior specification No. 924,335 issued 8th June 1909, the throats formed at the smaller ends of the truncated cones being gradually increased in diameter from the first to the last. 80

In order that the invention may be clearly understood I have hereunto appended an explanatory sheet of drawings, whereon:—

Figure 1 is a view of one form of the apparatus with an annular jet. Fig. 2 is an 85 enlarged cross section of the diaphragm or plate *b*. Fig. 3 is a plan of the said diaphragm or plate *b*. Fig. 4 is a view showing how the throats of the cones increase in diameter. Fig. 5 shows a modified arrangement of annular jet diaphragm and wherein the size of the annular channel or passage 90 may be varied by means of a spindle and hand wheel. Figs. 6 and 7 are sections of another form of diaphragm, and Fig. 8 is a 95 plan of the same.

The water, under pressure, passes from the tube *a* through the diaphragm *b* and issues as a jet of spray which passes across the space *c* of the suction chamber *d* into 100 the eduction tube *e* which latter, as will be noticed, has a series of conic contractions therein, which form truncated cones marked 1, 2, 3, 4 and 5, the throats of which preferably increase in size toward the final outlet 105 owing to the diminished velocity of the fluids passing therethrough.

f is the suction branch of the suction chamber, *g* a tube inclosing the eduction tube and *h* a tubular protecting casing. 110

The diaphragm *b* is made in a special manner being composed of a box *i* having

an outlet orifice j with a sharp edge at j^1 and an outwardly tapering mouth j^2 . Screwed into the box is a block k having inclined and converging openings k^1 and a 5 tapered central part l which depends into the mouth of the orifice j so that an annular opening or passage way is formed at m . It will be seen that the openings k^1 do not register exactly with the passage way m 10 the part at j^1 , which is flat at top, projecting inward and forming a partial floor at the bottom of the openings k^1 .

n is a packing ring which may be changed and be replaced by a thicker or thinner ring 15 according as it is desired to have a larger or smaller annular passage way m , this manner of adjustment being rendered desirable when the tube a is straight, thus rendering any externally operated screw adjustment 20 complicated or cumbersome. With this construction of diaphragm, the water from the openings k^1 cascades (see the dotted lines) over the edge j^1 and through the passage m forming a hollow annular jet the molecules 25 of which impinge at or about the point o and from this point, owing to the re-action, the water breaks up and spreads in the form of finely atomized spray which travels forward with but very slight diminution of 30 the original velocity of discharge. The orifices may be circular, as shown, or they may be rectangular. I prefer to use circular orifices. If desired I may use more than one cascading jet in the apparatus. Owing 35 to the cascading action a full flow of water does not take place through the orifice but only a partial flow with the result that water is economized, while, owing to the thorough atomization and practically undiminished 40 velocity of the jet, great efficiency is also obtained.

In the modified arrangement of annular jet shown at Fig. 5, the tapered part l is made in a separate piece and is adjustable 45 by means of a spindle r passing through a stuffing gland s and operated by a hand wheel t , this spindle being, at its inner end r^1 , screwed into a boss u made on the block k . The spindle, at its extremity, is secured in 50 position by the nut r^2 .

In the diaphragm shown at Figs. 6, 7, and 8, the size of the annular passage is varied by means of the spindle r as before. In this case the central tapered part l , to which the 55 spindle is secured, is provided with a plurality of projecting arms l^2 , the faces l^3 of said arms being screwed to engage with the screwed face i^2 of the box i .

Having now fully described my invention, what I claim and desire to secure by Letters Patent is:—

1. The combination in a hydraulic jet apparatus for extracting air, gas, or vapor, of a suction chamber having a diaphragm 60 removably seated therein and provided with

a central diverging jet orifice, and a block having a number of inclined openings located around the center thereof.

2. The combination in a hydraulic jet apparatus for extracting air, gas or vapor, 70 of a suction chamber having a diaphragm removably seated therein and provided with a central diverging jet orifice, a block having a number of inclined openings located around the center thereof, a conical part depending into said central diverging jet orifice, and means for adjusting the block 75 within said diaphragm.

3. The combination in a hydraulic jet apparatus for extracting air, gas or vapor, 80 of a suction chamber having a recessed diaphragm removably seated therein and provided with a central diverging orifice, a block adapted to screw into the recess of said diaphragm and having a number of 85 inclined openings located around the center thereof, and a packing-ring interposed between the seat of said recess and the bottom of said block.

4. The combination in a hydraulic jet 90 apparatus for extracting air, gas or vapor, of a suction chamber having a removable diaphragm with a screwed recess therein, said diaphragm having a central diverging jet orifice, and a tapered block depending 95 into said orifice and provided with extensions adapted to engage the screw-thread in the recess of said diaphragm.

5. The combination in a hydraulic jet apparatus for extracting air, gas, or vapor, of 100 a diaphragm having two orifices of different sizes therein which are in line but do not register the one with the other.

6. The combination in a hydraulic jet apparatus for extracting air, gas or vapor, 105 of a diaphragm having a screwed recess therein, a perforated block engaging said recess, and a diverging orifice in said diaphragm in line with but not registering with said recess. 110

7. The combination in a hydraulic jet apparatus for extracting air, gas, or vapor, of a diaphragm made in two parts, the one part having an orifice therein, the walls of which do not converge, and the other part 115 having a larger orifice therein and in line with the first-mentioned orifice and tapered means at the center of the larger orifice and depending into the smaller orifice.

8. The combination with a hydraulic jet 120 suction apparatus having an eduction tube provided with a series of truncated cones therein and communicating with one another, the throats of the said truncated cones gradually enlarging toward the final 125 outlet, of a diaphragm through which the water passes and means for causing the water to cascade as it passes through the diaphragm.

9. The combination with a hydraulic jet 130

suction apparatus having an eduction tube provided with a series of truncated cones therein and communicating with one another, the throats of the said truncated cones gradually enlarging toward the final outlet, of a diaphragm through which the water passes in annular jet formation and means for causing the water to cascade as it passes through the diaphragm.

10 10. The combination with a hydraulic jet suction apparatus having an eduction tube provided with a series of truncated cones therein and communicating with one another, the throats of the said truncated cones gradually enlarging toward the final outlet, of a diaphragm having a central jet orifice therein and whose wall does not converge, and adjustable tapered means depending into said orifice.

15 15. The combination with a hydraulic jet suction apparatus having an eduction tube provided with a series of truncated cones therein and communicating with one another, the throats of the said truncated cones gradually enlarging toward the final outlet, of a diaphragm having a central jet orifice therein and whose wall does not converge, and tapered means depending into said orifice so as to leave an annular water passage.

20 11. The combination with a hydraulic jet suction apparatus having an eduction tube provided with a series of truncated cones

therein and communicating with one another, the throats of the said truncated cones gradually enlarging toward the final outlet, of a diaphragm having a central jet orifice therein and whose wall does not converge, and adjustable tapered means depending into said orifice.

12. The combination with a hydraulic jet suction apparatus having an eduction tube provided with a series of truncated cones therein and communicating with one another, the throats of the said truncated cones gradually enlarging toward the final outlet, of a diaphragm having a central diverging jet orifice therein, and tapered means depending into said orifice so as to leave an annular water passage.

In testimony whereof I affix my signature in presence of two witnesses.

WILLIAM JOHNSTON FRAME.
